CLAIM

The ornamental design for a hand grip protector, as shown and described.

DESCRIPTION

FIG. 1 is a front elevational view of a hand grip protector, showing my new design;

FIG. 2 is a side elevational view of the hand grip protector of FIG. 1;

FIG. 3 is a rear elevational view of the hand grip protector of FIGS. 1 and 2;

FIG. 4 is a top plan view of the hand grip protector of FIGS. 1-3;

FIG. 5 is a bottom view of the hand grip protector of FIGS. 1-4;

FIG. 6 is a perspective view from the side of the hand grip protector best seen in FIG. 2; and

FIG. 7 is a perspective view of the opposite end of FIG. 6.
